CLAIM

The ornamental design for a brew time indicating device, as shown and described.

DESCRIPTION

FIG. 1 is a top perspective view showing our new brew time indicating device;

FIG. 2 is an exploded perspective view thereof, showing the various pieces;

FIG. 3 is front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings show portions of the brew time indicating device that form no part of the claimed design.

1 Claim, 5 Drawing Sheets
